PAINT BRUSH

Filed May 3, 1928

FIG. 1

FIG. 2

FIG. 3

Inventor

C. C. Lesiak

By Watson E. Coleman

Attorney

UNITED STATES PATENT OFFICE.

CHARLES C. LESIAK, OF FULLERTON, NEBRASKA.

PAINTBRUSH.

Application filed May 3, 1928. Serial No. 274,923.

This invention relates to paint brushes and it is an object of the invention to provide a device of this kind with means to effectively collect paint or other fluid which 5 would otherwise have a tendency to flow over or down the brush handle.

Another object of the invention is to provide a paint brush with means to collect paint or other fluid which may drip from 10 the bristles when the brush is in use, said means allowing the collected fluid to readily return to a pail or other container when the brush is being dipped or allow such collected paint or the like to flow back to the bristles 15 of the brush.

The invention consists in the details of construction and in the combination and arrangement of the several parts of my improved paint brush whereby certain important advantages are attained and the device rendered simpler, less expensive and otherwise more convenient and advantageous for use, as will be hereinafter more fully 20 set forth.

25 The novel features of my invention will hereinafter be definitely claimed.

In order that my invention may be the better understood, I will now proceed to describe the same with reference to the accompanying drawing, wherein:—

Figure 1 is a fragmentary view in side elevation illustrating a paint brush constructed in accordance with an embodiment of my invention;

35 Figure 2 is a view in edge elevation of the structure as illustrated in Figure 1 with a portion in section;

Figure 3 is a view in top plan of the structure as illustrated in Figure 1.

40 As disclosed in the accompanying drawing, 1 denotes a brush head provided with a conventional handle 2, said head having associated therewith in a well known manner the bristles 3, said bristles 3 being held to the head 1 through the medium of the metallic ferrule 4.

Associated with the ferrule 4 is the drip catcher D including a sleeve end portion 5 snugly surrounding the ferrule 4 and preferably soldered thereto although said sleeve 5 may be fixed to the ferrule 4 in any manner preferred.

The opposite end portion of the sleeve 5 is provided with an outstanding bead 6 substantially C-shaped in cross section with the

major diameter of such cross sectional configuration disposed in a direction lengthwise of the handle 2.

This bead 6 provides a trough 7, the major portion of the inner face 8 of which being open and the inwardly disposed free marginal portion of the bead 6 is slightly spaced from the adjacent portion of the ferrule 4 so that paint or other liquid dripping or running from the bristles 3 may readily enter and be collected within the trough 7.

It is to be noted that the free marginal portion of the bead 6 is disposed inwardly and that the cross sectional configuration of said bead is such as to have the portion of the bead immediately adjacent to the ferrule 4 disposed inwardly of the sleeve portion 5 of the catcher D.

At a desired point thereon the free marginal portion of the bead 6 is provided with a notch or recess 9 extending inwardly a material distance of the free portion of the bead and providing means to obtain an effective draining of the trough 7 when desired. It is also to be noted that the device 80 D is applied to the ferrule 4 in a manner whereby the portion of the bead 6 adjacent to the bristles 3 is spaced inwardly of the adjacent or outer margin of the ferrule 4 so the bristles 3 can be kept clean when the 85 brush is not in use.

The paint or other fluid dripping or running from the bristles is readily caught within the trough 7, the construction and configuration of which being such whereby 90 such collected paint or other fluid cannot be readily spilled out as the bristles are turned downwardly.

The space 10 between the ferrule 4 and the inwardly disposed free marginal portion of the bead 6 during a working operation will allow some of the paint or other fluid collected within the trough 7 to flow back on the bristles 3 and, as before stated, the paint or the like within the trough 7 is 100 adapted to be drained out through the recess or opening 9. The paint or the like collected within the trough 7 will not readily spill therefrom irrespective of the various positions assumed by the brush proper as the brush when swung into substantially a horizontal position the paint or the like within the upper portion of the trough will have a tendency to flow to the bottom portion of the trough, such portion of the paint or other 110

fluid which may pass out through the space 10 will be received upon the bristles 3.

In dipping the brush into a pail or other container the trough 7 may be readily 5 drained out by giving a slight tip to the brush in a direction to lower the recess or opening 9 so that the paint or other fluid within the trough will readily pass out there- through.

10 With the use of the drip catcher D a substantially clean job of painting can be done.

Soldered or otherwise secured at a desired point to the bead 6 is a hook 11 adapted to be engaged over the upper marginal portion of 15 a pail or other receptacle to prevent the brush from dropping down into the paint or kindred fluid.

From the foregoing description it is thought to be obvious that a paint brush 20 constructed in accordance with my invention is particularly well adapted for use by reason of the convenience and facility with which it may be assembled and operated, and it will also be obvious that my inven-

tion is susceptible of some change and modification without departing from the principles and spirit thereof and for this reason I do not wish to be understood as limiting myself to the precise arrangement and formation of the several parts herein shown 25 in carrying out my invention in practice except as hereinafter claimed.

I claim:—

The combination with a paint brush head having a ferrule fitted thereabout, of a drip 30 receptacle of substantially C-shaped cross- sectional design surrounding said ferrule with the open face directed toward the same, and a sleeve depending from the lower edge 35 of the receptacle and snugly engaging about the ferrule, the top edge of the receptacle being directed downwardly toward and spaced slightly from the ferrule, said receptacle having a recess cut down through the top to form a drain opening.

40 In testimony whereof I hereunto affix my signature.

CHARLES C. LESIAK.
